(57) CLAIM

The ornamental design for a bottle lid as shown and described.

DESCRIPTION

FIG. 1 is a perspective view of the bottle lid showing my design;

FIG. 2 is a front elevation view thereof;

FIG. 3 is a back view thereof;

FIG. 4 is a left-side view thereof;

FIG. 5 is a right-side view thereof;

FIG. 6 is a top plan view thereof; and,

FIG. 7 is a bottom view thereof.

Portions of the bottle lid shown in broken lines form no part of the claimed design.

1 Claim, 7 Drawing Sheets

See application file for complete search history.
